UNITED STATES PATENT OFFICE.

FRANK W. ROWE, OF OAKLAND, CALIFORNIA.

WINDOW-SHADE DEVICE.

1,153,521.

Specification of Letters Patent. Patented Sept. 14, 1915.

Application filed June 12, 1914. Serial No. 844,725.

To all whom it may concern:

Be it known that I, FRANK W. ROWE, a citizen of the United States, residing at Oakland, in the county of Alameda, State of California, have invented certain new and useful Improvements in Window-Shade Devices; and I do hereby declare the following to be a full, clear, and exact description of the invention, such as will enable others skilled in the art to which it appertains to make and use the same.

This invention relates to window shades, and has for its object the provision of a novel window shade the roller of which may be adjusted vertically upon a window frame whereby air may be allowed to enter a room above the shade.

An important object is to provide a shade of this character which may be pulled bodily downwardly and which is returned to its original position by spring tension when the holding catch is released.

More specifically the object of the invention consists in the provision of a spring roller stationary upon a window frame and carrying vertically movable brackets supporting the shade roller.

Another object of the invention is to provide a device of this character which will be simple and inexpensive in manufacture, efficient and durable in use, and a general improvement of the art.

With these and other objects and advantages in view, my invention consists in the novel construction, arrangement and combination of parts to be hereinafter more fully described and claimed, and illustrated in the accompanying drawing in which:

Figure 1 is a view of a window having my device applied thereto, showing the shade roller in its lowest position, Fig. 2 is an enlarged elevation of my device, Fig. 3 is a side elevation thereof, Fig. 4 is a longitudinal sectional view through the spring roller and its associated parts, Fig. 5 is a vertical sectional view through the winding drum and the guide bracket, and Fig. 6 is a detail cross sectional view through one of the guide brackets.

Referring more particularly to the drawings in which like numerals designate corresponding parts throughout the several views, the numeral 5 indicates a window frame to which my device is adapted to be secured. Secured adjacent the sides of the frame 5 are brackets 6 adapted to support my novel spring roller designated as a whole by the numeral 7. The spring roller comprises a tubular member 8 provided at its center with a disk 9 secured therein and having reduced lateral extensions 10 provided with holes for a purpose to be described. The outer ends of the tube 8 are closed by plugs 11 provided with central apertures for the passage of rods 12 which are screw threaded upon their inner ends and which are provided upon their outer ends with squared portions 13 engaging within slots 14 in the brackets 6 by means of which the roller 7 is supported. The inner ends of the rods 12 have threaded thereon bushings or sleeves 15 which, together with the rods 12 are provided with holes for the reception of the ends of coil springs 16 which have their other ends engaged within the holes in the extensions 10 of the disk 9. Collars 17 are disposed upon the outer ends of the tube 8 and have their horizontal flanges secured upon the tube by screws 18 which pass through the flanges through the tube and into the plugs 11 whereby the plugs 11 are held within the tube 8. Cable drums or spools 19 are loosely mounted upon the tube 8 adjacent its ends and are adjustably secured in relation thereto by means of screws 20 which pass through the drums and engage within selected ones of a plurality of holes 21 formed in the vertical flanges 22 of the collars 17.

In order that the shade roller 23 may be vertically movably mounted upon the window frame 5 I provide guides 24 secured upon the window frame below and in alignment with the drums 19. Each of these guides comprises an upper head 25 secured upon the window frame as at 26 and provided with a circular recess 27 and a hole 28 through its upper portion communicating with the recess. A tube 29 preferably cir-

cular in cross section has its upper end disposed within the recess 27 and its lower end disposed within the recess 30 in a lower head 31 secured upon the window frame as at 32. 5 The head 31 has a hook 33 formed thereon for a purpose to be described.

The shade supporting means comprises a pair of brackets 34, one provided with the usual slot 35 for the reception of the squared 10 end of the projection on one end of the shade roller 23, and the other provided with the usual circular hole for the reception of the pin upon the other end of the shade roller. The brackets 34 are provided with heads 36 15 provided with longitudinal openings 37 through which extend cables or cords 38 which extend upwardly and are trained about the drums 19. The brackets 34 are mounted relatively to the guides 24 by having the heads 36 disposed within the circular tubes 29 and the flat plate portions extending through slots 39 formed in the front of the tubes. It will thus be seen that the brackets 34 are vertically slidable within 20 the tubes. 25

In order that the shade roller 23 may be pulled down I provide an ear 40 upon one of the brackets 34 through which is secured one end of a chain 41 having a plurality of 30 rings 42 secured thereon. When the shade roller is pulled down any one of the rings 42 may be engaged upon the hook 33.

The device is applied to a window by inserting the squared portions 13 within the 35 slots 14 in the brackets 6 whereby the spring roller 7 will be supported and the outer ends of the springs 16 will be held stationary. As the plugs 11 are revoluble upon the smooth shanks of the rods 12 the springs 16 40 are put under tension by rotating the collars 17. After the spring has been wound somewhat the drums 19, being disconnected from the collars 17, are then turned so as to raise the brackets 34 upwardly into engagement with the heads 25. The drums 19 are then secured to the collars 17 by inserting the screws 20 through the drums 19 45 and into the proper holes 21 in the flanges 22 of the collars 17. The shade roller 23 will then be held firmly in its highest position as the cables 38 pass through the openings 37 in the shade roller supporting brackets 34 and are knotted thereunder. When the chain 41 is pulled to lower the 50 brackets 34 the springs 16 are put under greater tension so that when the rings 42 are released from the hook 33 the tension of the springs will rotate the tube 8 and consequently the collar 17 and thereby the drums 19 which will then wind up the cables 38 55 and return the shade to its original position. If it is desired at any time to vary the tension of the springs it is a simple matter to

do so as it is merely necessary to remove the screws 20 and insert them in different holes 65 21 in the flange 22 of the collar 17.

It is to be observed that my device does not in any way interfere with the action of the shade which is absolutely independent of the operation of my device. 70

It will thus be seen that I have provided novel means whereby a shade roller may be moved bodily vertically upon a window frame for allowing proper ventilation within a room. 75

It will be readily understood that I reserve the right to make various changes in the form, construction, arrangement and combination of parts without departing from the spirit of the invention or limiting 80 the scope of the subjoined claims.

Having thus described my invention, I claim:

1. A device of the character described comprising a spring roller provided upon its 85 ends with collars rigidly secured thereto and provided with a plurality of holes, drums mounted on said spring roller and revolvably adjustable thereon by the engagement of screws within selected ones of said holes, 90 brackets disposed below said drums and slidably engaged by shade roller supporting brackets, cables trained about said drums and connected with said shade roller supporting brackets and means connected with 95 said curtain roller brackets for moving them downwardly, said movable brackets being returnable by the tension of said spring roller.

2. In a device of the character described, 100 a spring roller comprising a tubular member provided at its center with a disk, plugs secured within the ends of said tubular member and provided with openings, rods passing through said openings and supported upon fixed brackets, springs connected with said disk and said plugs, collars secured upon the ends of said tubular member and provided upon their peripheries with a plurality of holes, drums mounted on said tubular member, and screws passing through 110 said drums and engaging selected ones of the holes in said last named collars, whereby the tension of the springs may be varied by rotation of said tubular member after the 115 removal of said screw without removing said rods from said supporting brackets.

3. In a device of the character described, 120 a spring roller comprising a tube, a disk secured within and at the central portion of said tube, a plug secured within each end of said tube and provided with an opening, a rod revolvable through each of said openings and provided at its outer end with a squared head engageable with a bracket, a 125 spring connecting said disk with the inner

end of each of said rods, a flanged collar secured upon each end of said tube and provided with a plurality of transverse holes, a winding drum mounted on each end of said tube, and a screw extending through each drum and through a selected one of the holes in each collar, whereby upon removal of said screws said tube may be rotated to vary the tension of said springs without

shifting the position of an article suspended by flexible members trained about said drums.

In testimony whereof, I affix my signature, in the presence of two witnesses.

FRANK W. ROWE.
